MATCH BOX DISPENSER

Mary Phyne Newell, 5475 Cabanne Ave., St. Louis, Mo.

Filed Sept. 16, 1958, Ser. No. 761,443

8 Claims. (Cl. 206—31)

This invention relates to improvements in match dispensers and match boxes adapted for use as match dispensers, and particularly to a dispenser which can be made from the commercially available commonly used match box for household matches.

Such matches are available on the market in boxes which comprise an open ended slide-on cover, an open top tray containing the matches positioned parallel to the width of the tray and a retaining insert strip placed across and on top of the matches to retain the matches therein.

More particularly, this invention relates to improvements in a vertically disposed apertured match box dispenser with a trough arranged to project outwardly from the lower front portion thereof.

The primary object of the present invention, therefore, is the utilization of the three component parts of the standard commercial match box as described above for the purpose of converting the said box into a match dispenser, wherein the open top tray is provided with a lower flexible portion thereof to obtain greater accessibility to any amount of the matches therein.

Other objects of this invention include the provision of trough arrangements directly associated with the flexible tray in the assembly of the three component parts of the dispenser.

Specifically, the flexible tray is devised so as to provide in the above-described dispenser a hinge-like lower portion of the tray wherein the lower sides thereof extend rearwardly in assembly to position the bottom of the tray in an upwardly oblique plane.

Thus, the lower front portion of the tray in assembly is foreshortened so that while the rear wall of the tray approximates that of the slide-on cover, the improved hinge-like lower side portions of the tray provide for the front portion of the tray adjacent to the inside front wall of the slide-on cover to approximate in assembly that portion of the cover extending from the top of the dispenser to the lower edge of the front cover opening so that the front edge of the bottom of the tray is disposed at the said lower edge of the trough opening, whereby any minimal amount of matches remaining in the tray become easily accessible.

In the accompanying drawings:

Fig. 1 shows the lower portion of a slide-on cover with a scored center tab on the lower front portion.

Fig. 2 shows the lower portion of an open top tray with the sides scored and a scored center slot in the bottom thereof positioned adjacent the rear wall of the tray.

Fig. 3 shows a right hand end of an insert strip with the trough base having scored side flaps.

Fig. 4 shows the strip in Figure 3 folded and opened for assembly.

Fig. 5 shows the slide-on cover in Figure 1 with the lower front portion opened and bent inwardly, and the trough in Figure 4 inserted into the front cover aperture.

2

Fig. 6 shows the scored sides of the tray opened for assembly.

Fig. 7 shows the assembly of the slide-on cover in Figure 1, the tray in Figure 2, and the trough in Figure 3.

5 Fig. 8 shows the end portion of the bent inwardly portion of the slide-on cover in Figure 5 inserted into the scored slot on the bottom of the tray.

Fig. 9 shows a trough base with a scored center tab to interlock with the scored center tab on the lower front 10 portion of the slide-on cover in Figure 1.

Fig. 10 shows the trough in Figure 9 with the scored center tab on the trough base thereof disposed in an interlocking position with the scored center tab on the lower front portion of the slide-on cover in Figure 1.

15 Fig. 11 shows the tray in Figure 2 with the scored center slot in the bottom thereof disposed medially to all edges thereof.

Fig. 12 shows a trough with separate scored center tabs on the trough base thereof.

20 Fig. 13 shows the assembly of a slide-on cover with the lower front portion thereof in the form of a lid, the tray in Figure 11 and the trough in Figure 12.

Fig. 14 shows the trough base of the trough in Figure 12 with one of the scored center tabs abutting the bottom 25 edge of the tray, and the other scored center tab inserted into the slot on the bottom of the tray in Figure 11.

The lower side wall portions 1 of the tray 2, shown in Figure 2, are scored to provide when opened hinge-like side wall flaps 3, as shown in Figure 6, so that the lower 30 portion of the tray 2 is flexible.

35 In assembly, side wall flaps 3 extend rearwardly and overlap upper side wall portions 4, and bottom 5 projects upwardly at an acute angle from lower edge 6 of rear wall 7 on a plane related to the outwardly extended trough 8, as shown in Figure 7, so that the front edge 23, shown in Figures 2 and 6, of bottom 5 is adjacent to the scored fold line 22 of the trough base 15, as shown in Figure 5.

40 A scored slot 9 is provided in bottom 5 of tray 2 and is disposed adjacent to and parallel with lower edge 6 of rear wall 7, as shown in Figures 2 and 6, for the retention in scored slot 9 of the end portion 10 of the lower front portion 11 of slide-on cover 12, as shown in Figures 7 and 8.

45 For employment with the open top trough match box dispenser, a scored center tab 13 is provided on lower front portion 11 of slide-on cover 12, as shown in Figure 1, which when opened forms in assembly an abutment for front edge 14 of trough base 15, as shown in Figure 5.

50 The trough base 15 of trough 8 is provided with scored side flaps 16, as shown in Figure 3, which when opened, as shown in Figure 4, abut the interior front wall 18 of slide-on cover 12, as shown in Figures 5 and 7, when trough 8 is inserted into the front cover aperture 19, as 55 shown in Figure 5.

55 As thus disposed, the side flaps 16 in combination with front edge 14 of trough base 15 abutting base 17 of opened scored center tab 13 on slide-on cover 12 provide a fixed position of trough base 15, as shown in Figures 5 and 7.

60 For employment with the open top trough match box dispenser, the slide-on cover 12 of which is shown in Figures 1, 5, 7 and 10, an interlocking brace 20, shown in Figure 10, may be provided as an alternative to the provision of the trough base scored side flaps 16.

65 As part of the interlocking brace 20, a scored center tab 21, positioned to open toward the scored fold line 22, is provided on the trough base 15, as shown in Figure 9.

70 The interlocking brace 20 is formed when the scored center tab 21 is opened and is inserted into the resultant opening of scored center tab 13 on slide-on cover 12, as

shown in Figure 10, which provides a fixed position of trough base 15. In assembly, the front edge 14 of trough base 15 abuts base 17 of the opened scored center tab 13 on slide-on cover 12, as shown in Figure 10.

For employment with the lid type of match box dispenser, wherein the lower front portion of the slide-on cover is devised as a lid to close down over the open top trough, as shown in Figure 13, the trough base 15 is provided with two scored center tabs 24 and 25, which are positioned apart and open toward each other, as shown in Figure 12. The scored center tab 24 is disposed medially on the scored fold line 22 on trough base 15, and the scored center tab 25 is disposed below center tab 24 and spaced inwardly from the adjacent front edge 14, as shown in Figure 12.

In assembly, the scored center tab 24 is opened and positioned to abut the front edge 23 of bottom 5 of tray 2, as shown in Figures 13 and 14, and scored center tab 25 is inserted into the scored slot 9 positioned on bottom 5, as shown in Figure 14. Both scored center tabs 24 and 25 thus disposed provide a locked position of trough base 15. In this structure, the scored slot 9 is positioned in the center of the bottom 5 of tray 2, as shown in Figure 11.

Having described my invention in detail, I claim:

1. A box such as a match box adapted to be converted into a vertically positioned dispenser, comprising an open-ended slide-on cover of rectangular cross section having front, back and side walls, one open end of the cover being its upper end and the other open end being its lower end when the box is vertically positioned as a dispenser, an open-top tray having bottom, side and end walls, one end wall of the tray being its upper end wall and the other end wall being its lower end wall when the box is vertically positioned as a dispenser, the length and width of the tray bottom corresponding to the length and width of the slide-on cover and the height of the walls of the tray corresponding to the height of the walls of the slide-on cover, the side walls of the tray being scored on lines extending from the corners of the tray at said lower end wall of the tray to points at the upper edges of the tray side walls spaced from said lower end wall of the tray, said tray side walls being adapted to be separated at said score lines thereby to form side flaps at the ends of said lower end wall of the tray, and said lower end wall thus being freed to fold inward at its line of juncture with the lower end wall of the tray to extend at an acute angle with respect to the bottom wall of the tray, said cover having its front wall scored to define a portion thereof adapted to be separated from the front wall and folded away from the front wall on a fold line extending transversely across the front wall to provide an opening in the front wall adjacent the lower open end of the cover, and a retaining strip adapted to form a trough, said strip having a main central panel adapted to form a front trough wall, side flaps integrally hinged to said main central panel at the sides thereof and adapted to be folded to extend at right angles to said main central panel to form trough side walls, and a bottom flap on said main central panel below said trough side walls forming a trough base, said trough side walls and said trough base being adapted for insertion in the opening made in the front wall of the cover with said

front trough wall angled upward and outward from the lower edge of the opening in the front wall of the cover and said trough base angled downward and inward, said trough base then being engageable by said freed lower end wall of the tray on insertion of the tray in the cover so that with the tray pushed substantially completely into the cover with the upper end wall of the tray substantially flush with the upper end of the cover, the lower end wall of the tray assumes an inwardly folded position angled upward from the lower end of the back wall of the cover toward the lower edge of the opening in the cover.

5 2. A box as set forth in claim 1 wherein the said portion of the front wall of the cover is hingedly connected to the front wall at the lower edge of the opening in the cover and is folded in to extend downward at an angle from the lower edge of the opening under the trough base.

10 3. A box as set forth in claim 2 wherein the lower end wall of the tray has a transverse slot and said portion of the front wall of the cover has a tab adapted to fit in said slot when folded in.

15 4. A box as set forth in claim 2 wherein said portion of the front wall of the cover has a center tab separable therefrom on score lines and adapted to be folded to extend upward from said portion of the front wall to provide an abutment for the bottom edge of the trough base.

20 5. A box as set forth in claim 4 wherein the trough base has triangular side flaps insertable in said opening in the cover and engageable with the inside of the front wall of the cover.

25 6. A box as set forth in claim 2 wherein said portion of the front wall of the cover has a tab defined by score lines adapted to be folded up to a position for engagement by the bottom edge of the trough base and trough base has a tab defined by score lines adapted to be folded down for interlocking in the slot made in said portion of the front wall of the cover by folding up the tab in the latter.

30 7. A box as set forth in claim 1 wherein said portion of the front wall of the cover is hingedly connected to the front wall at the upper edge of the opening in the cover and is folded out from the cover to provide a lid for the trough.

35 8. A box as set forth in claim 7 wherein the trough base is provided with two center tabs defined by score lines, one center tab being located for folding up in front of the top edge of the lower end wall of the tray, and the lower end wall of the tray having a transverse slot for receiving the other tab to interlock the trough base and the lower end wall of the tray.
